UNITED STATES PATENT OFFICE.

THOMAS ELLIOTT, OF BIRMINGHAM, ALABAMA, ASSIGNOR TO CONTINENTAL GIN COMPANY, A CORPORATION OF DELAWARE.

LOCK FOR COTTON-PRESS DOORS.

Application filed August 24, 1927. Serial No. 215,069.

My invention relates to cotton presses, more particularly to means for locking the opposed side doors thereof, and has for its object the provision of apparatus of the character designated which shall firmly hold the doors in place, when desired, and which shall embody means for gradually releasing the lock.

Locking means for cotton press doors, as heretofore known to me, have usually embodied a bar or bars extending across the ends of the press from one of the opposed side doors to the other. The bars were usually permanently connected to one of the doors and were each provided at its free end with an eye which fitted over a cam carried by the other door. A lever was employed to actuate the cam in order to bring the doors to proper position before pressing a bale of cotton and for releasing the doors after the bale was pressed.

While the foregoing arrangement has answered its purpose and has provided a very simple means for locking the doors, serious accidents have sometimes occurred due to the lever being suddenly thrown upward as the cams were turned to release the doors. This is due to the fact that, after the bale has been pressed, the cotton is under very high pressure, which exerts a great outward force against the doors of the press, tending to force them outwardly and to force the cams to release position. The heavy pressure of the cotton against the doors, of course, only acts through a very short distance, yet this short powerful expression acting on the lock mechanism as released, has sometimes led to the serious results above referred to.

In accordance with my invention, I have overcome the before mentioned difficulty by providing a door lock means adapted to be gradually released always under positive mechanical control, thereby avoiding possibility of accidents. Preferably the lock means embodies a wedge shaped lock member together with co-operating screw actuated complementary members for holding it in place. By employing the wedge principle, together with a screw for gradually releasing the wedge lock member, I am enabled to gradually permit the doors to ease away from the bale of cotton until its pressure has been expended, whereupon the locking bars may be disengaged and the doors let down.

Apparatus embodying features of my in-

vention is illustrated in the accompanying drawings, forming a part of this application, wherein

Fig. 1 is an end elevation of a cotton press having my invention applied thereto;

Fig. 2 is a plan view of the press with the superstructure removed;

Fig. 3 is a sectional view taken along the line III—III of Fig. 2; and

Fig. 4 is a sectional view taken along the line IV—IV of Fig. 2.

Referring now to the drawings for a better understanding of my invention I show a cotton press embodying two opposed side doors 10 and 11 and two end doors 12 and 13. The lower part of the press has been omitted from the drawing as it may be of any well known construction. The upper platen of the press is shown at 16 and is carried by suitable channels 17, as is well understood in the art. The end doors of the press are braced by a flange member 18 and by an upper channel member 19, said members being securely bolted to the doors. Extending across the lower ends of the press are structural steel members 21 having bearings as at 22 and 23, the bearings 22 and 23 serving as pivots for the side doors of the press whereby they may be let down when desired, to the dotted positions shown in Fig. 1.

Extending across the upper part of the front side door of the press are a pair of oppositely facing channel members 24 and 26, said channel members constituting a bracing means for the front door of the press. The rear door of the press is similarly provided with a pair of channel members 28 and 29. Carried by the opposed channel members and bolted between each pair are a pair of hook-like members 31, 32, 33 and 34, each having an inclined face as shown at 36, the inclined faces being adapted to coact with flanges 37 carried near the upper end of the end doors, so as to hold the end doors in place when cotton is being pressed. Carried by the rear channel members 28 and 29 are a pair of bars 38 and 39, the bars being bent over to form loops which are bolted between the ends of the channel members by a relatively large bolt 41, and a smaller bolt 42. The larger bolt 41 serves as a pivot permitting lateral movement of the bars, which is limited by the smaller bolt 42. The bars 38

and 39 have holes provided at their inner ends for the reception of pins 43 and 44 which serve as pivots for bars 46 and 47, which latter are adapted to extend across 5 the press to the opposite side door and swing vertically on said pivots. The bars 46 and 47 are also formed by bending over bar iron of suitable strength and are formed at their ends with hollow wedges as shown at 48 and 10 49. In order to prevent crushing of the wedge-shaped ends 48 and 49 a pair of filler blocks 51 and 52 are inserted therein and are suitably attached thereto. The bars on each side such as 39 and 47 with the wedge-shaped member 49, constitute an important 15 part of my improved locking means.

At each end of the channel 26 is secured a short flange 53, against which the side of the wedge-shaped end of the locking bar is 20 adapted to rest when the doors are in position. It will be seen by a consideration of Fig. 4 that the channel 26 is longer than the channel 24 so that the locking bar rests on the channel 26 when in locking position. 25 Carried between the channels 24 and 26 are a pair of bars 56 and 57 having end faces which are complementary to the sides of the wedge-shaped locking members and adapted to bear against said members on the sides 30 opposite the flanges 53. In order to hold the bars 56 and 57 in place, a pair of guides 58 and 59 are provided between the channels 24 and 26 and the members 33 and 34 are provided with holes 61 through which the 35 bars 56 and 57 extend and act as outer guide means for the bars.

The inner ends of the bars 56 and 57 are provided with inclined faces as shown at 62 and 63, which bear against a wedge 64 provided between the ends of the bars. The wedge 64 is provided with a screw and nut operating mechanism 66, the screw terminating in a crank 67 extending in front of the door of the press. It will be seen by referring to Fig. 1, that by means of the handle 67 the wedge 64 may be moved inwardly or outwardly and thus determine the position of the bars 56 and 57 with respect to the wedge-shaped locking members 48 and 49.

50 From the foregoing the operation of apparatus made in accordance with my invention will be apparent. When a bale of cotton is to be pressed, the doors 11, 12 and 13 are placed in position, the end doors 12 and 13 being held by the corner members 31, 32, 33 and 34. The bars 46 and 47 are turned over across the channel 26 so as to bear against the flanges 53, the doors 10 and 11 are brought toward each other to their proper relation and the crank 60 67 turned to cause the wedge 64 to force the bars 56 and 57 outwardly, which in turn forces the bars against the wedges 48 and 49. When this has been done the doors are firmly held in place and the press is ready for operation. 65 When the bale of cotton has been pressed and

it is desired to again open the doors, the crank 67 is turned in a direction to cause the wedge 64 to gradually release its pressure against the bars 56 and 57. The pressure of the cotton against the doors then gradually forces the doors outwardly until the pressure has been entirely reversed. When this point has been reached the bars 46 and 47 may be lifted up off the channel 26, and laterally to free them from the ends of said channel. The 70 doors 10 and 11 may then be opened wide.

From the foregoing it will be apparent that I have provided an improved locking means for the doors of a cotton press wherein the doors may be safely and readily released 75 and opened without danger to the operator.

While I have shown my invention in but one form, it will be obvious to those skilled in the art that it is not so limited, but is susceptible of various changes and modifications, 80 without departing from the spirit thereof, and I desire, therefore that only such limitations shall be placed thereupon as are imposed by the prior art or as are specifically set forth in the appended claims.

90 What I claim is:

1. In a lock for the opposed doors of a cotton press, a locking member for connecting the opposed doors and holding them in place, wedge means for securing the locking member to one of the doors, and screw actuated wedge means for gradually releasing the first mentioned wedge means.

2. A lock for the opposed doors of a cotton press, comprising a bar pivoted to one door and having a wedge adapted to engage the other door, a member carried by the said other door and having two inclined faces one of which coacts with said bar wedge to hold the doors in place, a lock wedge coacting with the other inclined face of the member to hold it in engaged relation with the bar wedge, and screw actuated means for slowly operating the lock wedge.

3. Locking means for the opposed doors of a cotton press conforming to claim 2 wherein a pair of pivoted bars extend across the ends of the press from one door to the other and wherein the lock wedge operates to simultaneously release both bar wedges.

4. In a lock for the opposed side doors of a cotton press, a bracing structure extending crosswise of each door, a link secured near each end to the bracing structure of one door and extending across the ends of the press to the bracing structure of the other door when the doors are in place, a wedge-shaped locking member carried by each link and adapted to be supported by the last mentioned bracing structure, a guide fixedly secured to said bracing structure near each end thereof and adapted to bear against the outer side of the locking members, a pair of bars having faces complementary to the wedge members, common wedge means for holding the bars in contact

with the locking members, and a screw for slowly actuating the wedge means to release the locking members.

5. In a press, lock means for the opposed side doors thereof comprising an articulated connection at each end of the press, each connection being pivoted to one door to swing laterally and having a pivot permitting its free end to swing vertically, a wedge on the 10 free end of each connection, wedges on the other door coacting with said first mentioned wedges to hold the doors in locked relation,

and a common means for releasing said coacting wedges.

6. In a press, lock means for the opposed side doors thereof comprising a connection mounted at each end of one door and adapted to swing vertically and laterally, a wedge on the free end of each connection, wedge means on the other door adapted to coact with the 15 wedges on the connections, and screw means to release said door wedge means.

In testimony whereof I affix my signature.
THOMAS ELLIOTT.
